Patented July 6, 1915.

UNITED STATES PATENT OFFICE.

BENJAMIN DENVER COPPAGE, OF WILMINGTON, DELAWARE.

SAVE-ALL BOX.

1,145,559.

Specification of Letters Patent.

Patented July 6, 1915.

Application filed March 4, 1915. Serial No. 12,153.

To all whom it may concern:

Be it known that I, BENJAMIN DENVER COPPAGE, a resident of Wilmington, Delaware, (whose post-office address is care of 5 The Pusey & Jones Company, Wilmington, Delaware,) have invented a new and useful Improvement in Save-All Boxes, which invention is fully set forth in the following specification.

10 The present invention is an improvement in save-all boxes for use under a Fourdrinier wire of a paper-making machine, the function of these boxes being to catch water and stock. This water and stock are recovered 15 and utilized, and hence it is necessary that the boxes should be of non-rusting material, as rust would be ruinous to the paper. For a long time these boxes have been made of wood, and in recent years some have been 20 made of metal. It is necessary that these boxes should be light enough in weight to be manually handled, as it is necessary to remove them when removing or replacing a Fourdrinier wire, and it has been experienced 25 that, in modern paper-making machines capable of producing paper 200 inches or more in width, the old wooden save-alls as well as the metal save-alls heretofore proposed are commercially impracticable, due 30 to the weakness of the boxes which caused them to collapse under the weight of the body of water and stock collected.

Under these conditions the necessity for a light, strong, durable save-all became 35 acute, and the object of the present invention is to provide a device which will answer these requirements, which can be readily put in place under the wire and removed manually, and which at the same time can 40 be filled to overflowing, while being supported only at its extreme ends, without danger of collapsing.

It has been observed that, in connection 45 with save-alls heretofore employed, and which were provided with flat bottoms and vertical sides, the sides of the box fall either in or out when the box collapses; and while cross-bracing helped somewhat, it did not provide a complete remedy for the difficulty 50 inasmuch as the great weight of the water would cause the sides to collapse between the braces.

More specifically, then, the present invention provides a light and strong receptacle, 55 the sides of which are so constructed as to

prevent collapse under any of the conditions encountered in actual, commercial use.

The invention will be better understood by reference to the accompanying drawings, wherein—

Figure 1 is a perspective view of a save-all box constructed in accordance with the invention; Fig. 2 is a transverse section on the line 2—2 of Fig. 1; and Figs. 3 and 4 are views similar to Fig. 2 of slightly modified forms.

Referring to the drawings, wherein like reference numerals indicate like parts, 5 is the front stand or support for one end of the save-all and 6 is the other stand or support for the other end. The front stand is provided with a roller 7 in order to facilitate the removal of the save-all from under the Fourdrinier wire. The bottom 8 of the save-all, which is preferably formed 75 of a long strip or plate of brass or other composition, is suitably secured to the sides thereof. As here shown each side of the save-all is composed of two strips or plates 9 and 10, preferably of the same material as 80 the bottom 8, said strips or plates being angularly arranged with relation to each other and, as here shown, being secured to the bottom 8 by a row of rivets 11. Preferably each of the outer plates 9 has a substantially 85 right angle bend therein and the two longitudinal extremities of each inner plate 10 are bent so that the lower extremity 10^a is parallel with the horizontal part of said outer plate 9 and the upper extremity 10^b is 90 parallel with the vertical part of said plate 9. In order to secure the maximum strength 95 of connection between the side plates 9 and 10 and the bottom 8, each longitudinal edge of the latter projects between extremity 10^a and the horizontal part of the outer plate, the rivets 11 passing through said extremities, the bottom 8 and said horizontal parts, thus securing the bottom and sides fixedly together. This connection between the sides 100 and bottom renders it practically impossible to accidentally separate the parts or rupture the union. The upper edges of the sides 9 and 10 are also suitably fastened together and the structure endowed with greater rigidity by suitable connecting means, as rivets 12, and there is preferably secured between each extremity 10^b and the vertical part of the outer plate 9 one member of a metallic angle piece 13, said piece being preferably 105

110

secured in position in the same way that the bottom 8 is fastened to the sides, the presence of these angle pieces materially adding to the rigidity of the structure.

5 One end of the save-all is closed by an end-piece 14, which is suitably secured in place and which is of suitable construction. As herein shown this end-piece is provided at its top with an angle-piece 15. Bracing members 16 and 17 assist securing said end-piece to the side walls of the save-all. Between said side walls are carried a plurality of transverse braces 18 provided with end flanges 19, the whole being preferably secured in place by rivets 20. In the commercial boxes all of the braces 18 are made of light brass tubing except the one, 18', nearest the closed end-piece 14, which is made much heavier for withstanding the stress of 10 the "porter-bar" which is the tool used by the workmen in removing the save-all from stands 5 and 6. To remove the save-all box one end of the porter-bar is placed over the end 14 of the box and under said brace 18'. By then bearing down on the other end of 15 the bar, the farther end of the save-all is elevated from its stand and the whole weight rests on the roller 7. The box at this time is free from water and can be readily and 20 easily removed from under the wire.

As illustrated, the end of the box opposite that which is closed by end-piece 18 is left open and unobstructed. The water runs out of this open end into a common drain, and it 25 is not at all unusual, when the drainage is not in good condition, for the water to back up until the save-all is full to overflowing. By the present construction the walls and bottom of a save-all box, 200 inches or more 30 in length, may be made of sheet brass less than one-sixteenth of an inch thick and yet be strong and rigid enough to sustain, for an indefinite period, the weight of such an overflowing volume of water, the box at the 35 same time being light enough to permit of manual removal from under the wire.

The constructions shown in Figs. 3 and 4 are identical with the construction of Figs. 1 and 2, except that in Fig. 3 the angle piece 40 is omitted and the vertical part of each outer wall 9 and the extremities 10^b are riveted directly together. The same construction is formed in Fig. 4 except that the inner member 10 is provided with an extension 21 which 45 is integral therewith, and the other inner member 10 is provided with an apron 22.

The construction described is such that the bottom 8 and side plates 9 and 10 may be made from long narrow strips of composition or sheet brass, which are obtainable on the open market, whereas wider strips of the desired material could not be obtained on the open market. The use of shorter, wider strips would necessitate cross-seams, 55 which are very objectionable on account of

their weakness and added weight—all of which is avoided by the construction described.

The triangular space between the side plates 9 and 10 is preferably open to the 70 atmosphere. Each outer plate 9 is preferably continuous and imperforate throughout its length, as a stronger and more rigid structure is thereby obtained. Any break in these outer bracing plates 9 directly affects 75 the strength and rigidity of the structure as a whole and, as before stated, these walls are therefore preferably imperforate.

While for the purpose of illustration several expressions of the inventive idea are 80 herein shown and described in detail, it is to be understood that the invention is not limited to the constructions shown, but that the inventive idea is susceptible of various mechanical expressions within the limits of 85 the appended claims.

What is claimed is:—

1. A save-all box provided with a bottom and sides, the sides of said box being triangular in cross-section. 90
2. A save-all box provided with a bottom and sides, the sides of said box being triangular in cross-section and being riveted to said bottom.
3. A save-all box provided with a bottom 95 and sides, each side being composed of two plates triangularly arranged in cross-section, and means securing the longitudinal edges of said bottom between said plates.
4. A save-all box provided with a bottom 100 and sides, each side being composed of two plates triangularly arranged in cross-section, and rivets securing the longitudinal edges of said bottom between said plates.
5. A save-all box provided with a bottom 105 and sides, each side being composed of two plates triangularly arranged in cross-section, and rivets securing the longitudinal edges of said bottom between said plates, said rivets passing through said bottom and 110 the plates on both sides thereof.
6. A save-all box provided with a bottom and sides, each side being composed of two imperforate plates triangularly arranged in cross-section, rivets securing the longitudinal edges of said bottom between said plates, and means securing together the other longitudinal edges of each pair of plates. 115
7. A save-all box provided with a bottom and sides, each side being composed of two plates triangularly arranged in cross-section, rivets securing the longitudinal edges of said bottom between said plates, said rivets passing through said bottom and the plates on both sides thereof, an angle member, and means securing said member between said plates. 120
8. A save-all box provided with a bottom and sides, each side being composed of two plates triangularly arranged in cross-section. 125

tion, rivets securing the longitudinal edges of said bottom between said plates, said rivets passing through said bottom and the plates on both sides thereof, an angle member, and rivets securing said member between said plates.

9. A save-all box provided with a bottom and sides, the sides of said box being triangular in cross-section, and cross braces secured between said sides.

10. A save-all box provided with a bottom and sides, each side being composed of two plates triangularly arranged in cross-section, means securing the longitudinal edges of said bottom between said plates, and cross braces secured between said sides.

11. A save-all box provided with a bottom and sides, each side being composed of two imperforate plates triangularly arranged in cross-section, rivets securing the longitudinal edges of said bottom between said plates, means securing together the other longitudinal edges of each pair of plates, and cross braces secured between said sides.

12. A save-all box provided with a bottom and sides, each side being composed of two plates triangularly arranged in cross-section, rivets securing the longitudinal edges of said bottom between said plates, said rivets passing through said bottom and the

plates on both sides thereof, an angle member, means securing said member between said plates, and cross braces secured between said sides.

13. A save-all box provided with a bottom and sides, each side being composed of two imperforate plates triangularly arranged in cross-section, rivets securing the longitudinal edges of said bottom between said plates, and means securing together the other longitudinal edges of each pair of plates.

14. A save-all box provided with a bottom and sides, each side being composed of two imperforate plates triangularly arranged in cross-section, rivets securing the longitudinal edges of said bottom between said plates, and means securing together the other longitudinal edges of each pair of plates, an angle piece being riveted between said other longitudinal edges of each pair of plates.

In testimony whereof I have signed this specification in the presence of two subscribing witnesses.

BENJAMIN DENVER COPPAGE.
